PROVISION OF WIRE RIPS IN CANISTERS

Peter Bogner, London, England, assignor to Saml. Hanson & Son, Limited, London, England, a British company

Application March 7, 1940, Serial No. 322,748
In Great Britain December 22, 1938

6 Claims. (Cl. 113—15)

This application corresponds to the application of Peter Bogner, Serial No. 37,353/38, which was filed in Great Britain, December 22, 1938, and Serial No. 3,302/39, which was filed in Great Britain, January 31, 1939.

This invention is for improvements in or relating to the provision of wire-rips in canisters, or the like, and has for an object to facilitate retention of the wire in a desired location.

In the present specification and claims the term "canister" is used generically to include all sheet metal containers irrespective of the shape, form or dimensions such containers may have.

Another object of the invention is to provide for the manufacture of a can end-closure provided with a rip-wire which is held securely in place by being clinched in a ridge or groove formed in the material of the end-closure, so that during the seaming of the end-closure to the can-body the wire cannot be displaced from its proper position.

A further object is to provide a can end-closure having a rip-wire located in place in a ridge or groove in the end-closure with the walls of said ridge or groove pressed together to indent the rip-wire into them so as to secure the rip-wire in place and also form a line of weakening facilitating opening of the finished can by the rip-wire.

Yet another object is to provide a can end-closure which has a rip-wire secured to it and which can be readily seamed to a can-body by a normal seaming process.

A still further object is to provide an improved end-closure which has a rip-wire protruding at one end to the outside of the end-closure, and which can readily have the rip-wire clinched in place without risk of splitting the material of the end-closure in the neighbourhood of the location where the wire projects through the end-closure.

The end-closure disclosed herein is claimed in my copending application, Serial No. 351,619, filed August 6, 1940.

According to one aspect of the invention there is provided the method of securing a rip-wire in a desired location on a canister or the like, which comprises the step of causing the portion of the canister or the like along which the wire is to be disposed to be engaged progressively along its length by a pair of opposed grippers so shaped and disposed as to force the material of said portion of the canister or the like into the form of a re-entrant channel or substantially closed tube embracing the wire within it. The

said portion of the canister or the like on the one hand and the opposed gripper on the other hand are caused to move relatively to one another so that the channel or tube is formed progressively from one end to the other, or through a closed circuit commencing from and finishing at a chosen point therein. It will be appreciated that the formation of the said channel or tube serves to hold the rip-wire in its required position in such a way that the wire cannot become accidentally displaced. The wire may be fed to the said portion of the canister or the like so as to come into engagement with the latter immediately in advance of the grippers, or it may be already disposed along the desired location on said portion of the canister or the like before the material thereof is clinched around the wire. The said portion of the canister or the like may be an end-closure or a body portion.

In carrying out the present method the position of the rip-wire may be controlled by urging it into a desired location on the canister or the like immediately in advance of the grippers. This may be performed by means of a presser member arranged to engage the wire and urge it into the desired location. Such control of the position of the rip-wire is particularly useful when the wire is fed as aforesaid so as to come into engagement with the said portion of the canister or the like immediately in advance of the grippers, and in this case the presser member may be formed with a guide-way for the wire.

The method according to the invention may be employed for securing the rip-wire in a pre-formed groove in the said portion of the canister or the like, and in this case the said opposed grippers are operated in such manner as to close or partially close the mouth of the groove to clinch the wire in place. The position of the rip-wire may be controlled as aforesaid by urging it to the bottom of the groove immediately in advance of the grippers.

In applying the method according to the invention for securing a rip-wire within a groove extending around an end-closure of a canister with said groove discontinued to form a gap, the wire may be first inserted through an opening at one end of the groove at the gap, and the walls of the groove may subsequently be forced together by the grippers progressively along the groove from the end thereof at which the wire is inserted. The wire may be fed from the outside of the closure inwards, or it may be fed to

the groove from the inside of the closure. In the first alternative a sufficient length of wire is inserted before the clinching operation is commenced, but in the second alternative the wire may if desired be fed continuously to the closure as the clinching operation proceeds.

The invention further provides a method of procedure according to which, after the material of the said portion of the canister or the like has been formed as aforesaid to embrace the wire within it, the sides of the wire-embracing channel or substantially closed tube are pressed towards one another and against the wire so as to force the wire into the material of the canister or the like.

According to a further provision of the invention apparatus for securing a rip-wire in a desired location on a canister or the like comprises two opposed grippers formed with co-operating clinching surfaces, with said grippers so formed and so mounted that a relative rolling movement between said clinching surfaces is permitted, means for supporting in position to be engaged between said opposed grippers a portion of a canister or the like along which a rip-wire is to be located, and means for causing a relative advancement between said portion of the canister or the like and the grippers, with said portion of the canister or the like disposed between the grippers in such manner that the relative rolling motion between the clinching surfaces of the grippers will cause the portion of the canister or the like to be urged to a formation to embrace the rip-wire. The grippers may be constituted by rollers having circular rims of frusto-conical form with edges at their largest diameters which are directed towards one another so as to grip portions of the material of the canister or the like which are on opposite sides of the rip-wire and urge said portions together around the rip-wire.

The apparatus may comprise an additional pair of opposed grippers formed with co-operating pressing surfaces arranged to engage with the walls of the re-entrant channel or substantially closed tube formed on the canister or the like by means of the first-mentioned grippers, means for mounting said additional grippers to permit a relative rolling movement between their pressing surfaces, and means for advancing relatively to one another said portion of the canister or the like and said additional grippers with the portion of the canister or the like disposed between the additional grippers.

According to a further aspect of the invention there is provided for a canister an end-closure having a central depression to fit within the can-body and a marginal flange for interfolding with the can-body, and having the material of the closure between said depression and flange continued outwardly from said depression in the form of a shoulder and a ridge extending around said shoulder, and having a rip-wire contained in said ridge and the walls of the ridge clinched together to grip the rip-wire. The end-closure may also have the walls of the ridge pressed together sufficiently to cause the rip-wire to be indented in to the material of said walls.

A further provision of the invention consists in an end-closure for a canister which end-closure is formed with a groove to receive a rip-wire and has an end-face of the groove apertured for the passage of the rip-wire, with the aperture raised above the junction of the groove with those portions of the material of the can-

ister which are displaced laterally of the groove.

Certain preferred ways of carrying out the invention will now be described with reference to the accompanying drawings which illustrate by way of example one form of apparatus for securing a rip-wire in place on an end-closure of a canister, as well as certain modifications and certain preferred forms of end-closures.

In the drawings—

10 Figure 1 is a side elevation, partly in central cross-section, showing one form of apparatus for securing a rip-wire in place on an end-closure;

Figure 2 is a plan view, partly in cross-section, taken on the line 2—2 of Figure 1, of the parts 15 shown in Figure 1;

Figure 3 is a cross-sectional view of certain of the parts shown in Figure 1 and is taken on the line 3—3 of Figure 1;

Figure 4 is an enlarged detail view in cross-section of a portion of an end-closure as it appears before the rip-wire is applied to it;

Figure 5 is a view corresponding to Figure 4, but illustrating the clinching of the material of the end-closure around the rip-wire;

25 Figure 6 is a view in cross-section taken on the line 6—6 of Figure 5;

Figure 7 is a view corresponding to Figure 6 illustrating the commencement of a combined wire-inserting and clinching operation;

30 Figure 8 is a view corresponding to Figure 5, but having the cross-section taken in a plane containing the axes of the gripping rollers;

Figure 9 is a view corresponding to Figure 8, but illustrates the pressing of the rip-wire into the material of the end-closure;

Figure 10 is a fragmental view of a portion of an end-closure, seen from the underside, with the rip-wire secured in place;

35 Figure 11 is a view in perspective of a modified presser member;

Figure 12 is a view of a further modified form of presser member;

Figure 13 is a perspective view of a wired end-closure with a portion of the latter broken away to illustrate its cross-section;

45 Figure 14 is a somewhat diagrammatic view of a modified arrangement of parts of the apparatus for clinching the wire in place on an end-closure;

Figures 15, 16 and 17 are respectively an end-view, a side-view and a plan view of the end-portion of a wire-receiving groove or ridge;

Figure 18 is a side-view in cross-section of the end of the groove or ridge showing a rip-wire passing through it; and

Figure 19 is a side view of a reduced portion 55 of a continuous wire-receiving groove or ridge formed in an end-closure.

Like reference numerals indicate like parts throughout the drawings.

The apparatus illustrated in Figures 1 to 3 may 60 constitute a complete machine for securing rip-wires in place on canisters or the like, or it may form part of a machine which embodies other apparatus for performing different operations, such as wire-insertion or seaming, and in which the canister or the like or portions thereof are advanced from station to station so that the different operations may be performed at the different stations. To illustrate the invention the apparatus is shown as being adapted to secure a rip-wire in place on an end-closure of a canister, the end-closure being formed with a central depression surrounded by a shoulder 70 (see Figure 4) and a wire-receiving ridge 71 around the shoulder as described in my Patent 2,277,066.

75 Referring now to Figures 1 to 3, the apparatus

comprises a stationary frame 20 supporting opposed grippers in the form of rotatable rollers 21 and 22 secured respectively to driven shafts 23 and 24. A carriage 25 is movable along a guideway shown diagrammatically at 26 beneath the rollers 21 and 22. The carriage 25 has bearings in which a slidable rod 27 is mounted and additional bearings in which there is slidably mounted a presser member 30. The rod 27 has secured to it a holder 28 for supporting a can end-closure indicated generally at 47. The holder 28 has a contour corresponding to the underside of the depression in the end-closure and is arranged to grip the latter in any convenient way, for example magnetically or by suction. The rod 27 is urged to an inoperative position by a spring 29. The presser member 30 is disposed so as to lie opposite the ridge 71 in the end-closure.

The carriage 25 is arranged to be moved along the guideway 26 to bring the end-closure 47 beneath the gripper roller 21, an abutment, pawl or other device being shown diagrammatically at 37 for determining the required position of the carriage beneath the gripper roller. When the carriage has reached this position, pushers 33 and 34 mounted in a bracket 35 are arranged to be operated automatically or by hand by means of an operating rod 36 to urge the rod 27 and presser member 30 against their springs 29 and 31 so as carry the end-closure 47 into a position to co-operate with the gripper rollers 21 and 22 and so as to urge a toe 38 on the presser member 30 into the ridge 71.

The shaft 23 of the roller 21 is mounted in a bearing 48 which is slidably in the frame 20 towards and away from the shaft 24, for adjustment purposes. The bearing 48 carries at its lower end a flange or transverse extension formed with slots to receive fixing bolts 51, see Figure 2, provided for retaining the bearing 48 in place with the roller 21 in a desired setting. An adjusting screw 50 screwed into an extension of the frame 20 is provided to enable fine adjustments of the position of the bearing 48 to be made when the bolts 51 have been released. The adjustment of the position of the roller 21 enables the apparatus to be adjusted to suit can-closures of different sizes or to vary the extent to which the material of the end-closure is clinched around the rip-wire. The roller 22 is mounted in a bearing 52 which is also slidably mounted in the frame 20 being carried for example in a rectangular opening 53 in the frame 20. This mounting permits the roller 22 to be moved towards and away from the roller 21 to grip and release the material of the end-closure as required. The movement of the roller 22 may be effected manually or automatically, and in the drawings there is shown for this purpose a cam 54 secured to the shaft 24 and engaging with a cam roller 55 rotatable on a fixed bearing on the frame 20. The bearing 52 is urged by a spring 56 and plunger 57 in the direction to maintain the cam 54 in contact with the cam roller 55.

In order to effect relative advancement between the grippers 21 and 22 and the material of the ridge 71 of the end-closure, as is required, longitudinally of the ridge, either the end-closure or one or both of the rollers 21 and 22 may be caused to rotate. In Figures 1 and 2 the shafts 23 and 24 of the rollers 21 and 22 are shown as being provided with gears 58 and 59 fixed to them and in mesh with one another, and one of the gears namely the gear 58 is also in mesh with a driving gear 60 on a driving shaft which is driven in any convenient way.

The function of the gripper rollers 21 and 22 is to engage with the side walls 73 of the ridge 71 and urge said side walls together around the rip-wire which is indicated at 46. The material 5 of the ridge 71 of the end-closure is thus brought to a re-entrant channel formation or to the form of a substantially closed tube containing the rip-wire 46. The latter may be inserted in the ridge 71 before the end-closure 47 is brought into co-operation with the gripper rollers 21 and 22, or the wire may be inserted into the ridge 71 simultaneously with the clinching operation performed by the rollers 21 and 22. The apparatus shown in Figures 1 to 3 is adapted for the latter procedure.

The presser member 30, as shown in Figure 3, is formed with a longitudinal passage 39 through which the rip-wire may be fed. The member 30 has an extension piece 32 at its lower end in 20 which is formed a flared opening 40 leading to the passage 39 which after extending upwardly along substantially the whole length of the member 30 curves over so as to open tangentially on to the curved upper surface of the toe 38. 25 The flared opening 40 receives the rip-wire 46 from a delivery outlet 45 of a wire-guiding tube 41 fixed to the bracket 35. The wire is taken from a supply reel 44, passes between feed rolls 42 and is passed across a cutter 43 before entering the guide tube 41. Additional feed rolls 42 are provided near the upper end of the guide tube 41 to engage and advance the wire as required.

The frame 20 is extended to the right as viewed 35 in Figure 1 and carries a further set of shafts 23 and 24 mounted in bearings 48 and 52 which are adjustable in precisely the same way as those previously described, the shaft 24 being also arranged to be moved towards and away from the shaft 23 by a cam 54. On the right hand shafts 23 and 24 there are mounted an additional set 40 of grippers or presser members which take the form of rollers 63 and 64 which may have their rims slightly tapered as shown at 67, or cylindrical. After the end-closure 47 has had its 45 ridge clinched around the wire by the grippers 21 and 22, the carriage 25 is arranged to be released from the locating device 37 and moved to the right along the guideway 26 to bring it into co-operation with a further locating device 61. When thus moved the carriage is in position 50 to enable the end-closure 47 to be moved into co-operation with the presser rollers 63 and 64. A pusher member 62 slidably mounted in the bracket 35 is then operated to move the rod 27 against its spring and carry the holder 28 and the end-closure 47 upwardly to bring the ridge 71 between the presser rolls 63 and 64. The presser member 30 is at this stage kept inoperative by its spring 31 so as not to interfere with the pressing operation performed by the rollers 63 and 64.

In carrying out the method according to the invention an end-closure 47 is placed on the holder 28 and the carriage is moved to the right from the position shown in Figure 1 into engagement with the locating device 37. The end-closure 47 is in the form shown in Figure 4, and the ridge 71 is conveniently formed with a gap at one point in its length with one end of the ridge formed by an inclined wall 101 as shown in Figure 7. The end-closure 47 is placed on the holder 28 in such a position that when the holder is fed upwards by the pusher 33 the nip 70 between the gripper rollers 21 and 22 coincides 75

with the gap in the presser member 30 which is at the same time raised by the pusher 34 is brought to a position with its toe 38 engaging with the inclined wall 101 at the end of the ridge 71 as shown in full lines in Figure 7. In this position the toe 38 on the presser member is not fully inserted in the ridge and is permitted to lie partly out of the ridge by compression of a spring 108 interposed between the pusher 34 and the operating rod 36, means being provided, if desired, to hold the presser member in this position without pressing against the inclined wall 104. The curved upper end of the passage 39 in the presser member 30 serves to direct the wire 46 through an opening 102 provided for it in the end wall 101 of the ridge. The wire is inserted by operating the feed rolls 42 until a sufficient length projects through the hole 102 as indicated at 76. The feed of the wire is then discontinued and a sufficient length cut off to occupy the length of the ridge 71 and leave a short end protruding from the underside of the ridge as indicated at 75 in Figure 10.

The clinching operation is next commenced by driving the gripper rollers 21 and 22 through the gears 58, 59 and 60, these rollers having previously been at rest. The roller 21 engages frictionally with the shoulder 70 of the end-closure and the roller 22 engages frictionally with its marginal flange 72 which extends outwardly from the ridge 71. By this frictional engagement the end-closure 47 is caused to rotate and is permitted to do so by the rod 27 being rotatably mounted in the carriage 25. At the same time the cam 54 commences to urge the gripper roller 22 towards the roller 21. The gripper rollers 21 and 22 commence to grip the end portion of the ridge 71 with a slight pressure and their pressure on the ridge is gradually increased to a maximum just after the inclined wall 101 at the end of the ridge has moved past the nip between the rollers 21 and 22. By this time the relative positions of the presser 30 and ridge 71 are approximately as indicated by the chain line showing of the presser 30 in Figure 7. The toe 38 of the presser has by then ridden fully into the ridge 71 and is serving to press the wire 46 against the bottom of the ridge. It will be appreciated that the presser member 30 acts on the wire 46 immediately in advance of the grippers 21 and 22 so as to hold the wire in the desired location just before the side walls 73 of the ridge 71 are forced together to embrace it. Figure 5 shows a cross-section through the ridge 71 slightly in advance of the nip between the rollers 21 and 22 and illustrates how the toe 38 fits into the ridge closely and in such a way as to leave only a sufficient space for the wire 46 above it. Figure 8 shows a similar cross-section at the nip between the rollers 21 and 22 and it will be seen from this figure how the latter serve to force the side walls 73 of the ridge 71 together to embrace the wire 46.

During the rotation of the rollers 21 and 22 the peripheries of the latter have a relative rolling motion and the side walls of the ridge 71 are thereby gripped and clinched together around the wire progressively from one end of the ridge to the other, the severed length of wire being initially fed at the required rate by the upper feed rollers 42 and being afterwards drawn into place in the ridge 71 by the relative rotation between the end-closure 47 and the presser member 30. The rolling motion of the grippers 21 and 22 is such as to avoid slippage between

either gripper and the corresponding side wall 73 of the ridge 71, so as to avoid any tendency to rupture the material of the end-closure. After a complete rotation of the rollers 21 and 22 the wire 46 will have been secured in the groove along the whole length of the latter and the rotation of the rollers is arrested, the cam 54 being so shaped that the rollers will gradually be separated, the separation commencing just before the final end of the ridge 71 is reached. Thus it will be seen that both at the beginning and at the end of the ridge 71, that is to say where there are transverse end walls to the ridge, the pressure of the clinching rollers is lessened or released entirely so as to avoid any tendency of splitting the material of the closure at the grooved end, and also to permit the end 75 of the wire which is left on the inside of the closure to pass out of the ridge 71.

As soon as the gripper rollers 21 and 22 have been released the push rod 36 is also released to enable the holder 28 to be retracted by its spring 29. The carriage 25 is then released from the locating means 37 and advanced further along the guide-way 26. The carriage may in some cases move to a station at which the end-closure with the wire inserted and held in place in the ridge is removed for subsequent seaming to a can-body when in that condition, for the clinching of the side walls 73 of the ridge 71 around the rip-wire 46 is sufficient to hold the latter firmly in place in the ridge. It is preferred however to perform a subsequent operation on the end-closure by moving the carriage 25 into engagement with the locating means 61 and then operating the pusher 62 which serves to raise the holder 28 without raising the presser member 30, to an extent to bring the central part of the end-closure against the additional gripper or presser roller 63 and the marginal flange 72 of the end-closure against the corresponding roller 64, with the initial end of the ridge 71 close to the gap between the rollers 63 and 64, the position of which will coincide with the gap in the ridge. The shafts 23 and 24 of the rollers 63 and 64 which were previously at rest are now caused to turn with a relative rolling movement through a complete rotation. At the beginning of their rotation the rollers commence rotating the end-closure by frictionally engaging the shoulder 70 and marginal flange 72 thereof. At the same time the rollers 63 and 64 are urged together by the cam 54 and commence gripping the clinched ridge 71 immediately after the initial end of the ridge has passed the rollers, and the action of the rollers serves to press the side walls 73 further together into the formation shown in cross-section in Figure 9. The pressing of the walls 73 together after commencing near the initial end of the ridge progresses along the ridge until near its final end whereupon the cam 54 releases the presser just before the complete rotation of the rollers has occurred. The pressing action of the rollers 63 and 64 is such as to force the wire 46 into the material of the side walls 73 of the ridge and thereby form thin places as indicated at 74 on the outside and inside of the ridge. The thin portion of the outer wall 73 of the ridge may conveniently form a line of weakening to facilitate opening the completed canister by the use of the rip-wire 46.

When the pressing of the walls 73 together has been effected along the length of the ridge the rotation of the rollers 63 and 64 is arrested and the pusher 62 is released so as to permit the hold-

er 28 to retract the end-closure 41 away from the pressing apparatus under the action of the spring 29. The carriage 25 is then moved along the guide-way 26 to a station at which the end-closure 41 is removed for subsequent seaming to a can-body. The end-closure will then take the form shown in Figure 13 and the projecting end 16 of the rip-wire may be formed to a loop as shown at 82 and anchored by solder or otherwise at 83 to the central part of the end-closure. During the subsequent seaming the end 15 of the rip-wire which is left inside the end-closure may be conveniently embedded in the seam to assist in ensuring proper operation of the rip-wire when opening the can.

While Figures 1 and 2 illustrate an arrangement in which the gripper rollers for clinching the ridge and for pressing its walls together are rotated manually or by power means about parallel axes and serve to rotate the end-closure frictionally, it will be appreciated that a large number of variations in the mounting and driving of the rollers may be made. For instance the end-closure may be mounted on a fixed support or holder and rollers such as 21 and 22 or 63 and 64 may be revolved around the axis of the end-closure so as to traverse the nip between the rollers along the ridge 11 from end to end thereof. Such revolution of the rollers as a whole may cause them to rotate each about its own axis due to the frictional engagement with the ridge or the rollers may be driven so as to rotate about their own axes in addition to being revolved about the axis of the end-closure. Alternatively one of the rollers may be held stationary and the other roller revolved around it so as to grip the ridge 11 in the end-closure against the first roller progressively along the length of the ridge. In a further modification the end-closure itself may be driven so as to rotate about its own axis and cause the rollers to rotate by frictional engagement with them.

It will further be appreciated that the axes of the opposed gripper rollers may if desired be inclined to one another and one or both of them may be inclined to the axis of the end-closure. The formation of the rims of the gripper rollers may be varied as desired to suit the arrangement of the parts and the formation to which the ridge 11 is to be clinched.

In the construction shown in Figures 1 and 2 the clinching rollers 21 and 22 are formed with frusto-conical rims 65 with their portions which are of greatest diameter directed towards one another at the nip between the rollers so as to force the side walls 13 of the ridge to a re-entrant formation to grip the wire. These portions of the rollers which are of greatest diameter are indicated at 66 and as shown in Figures 5 and 8 they are rounded in cross-section to avoid the formation of a sharp edge. The end faces of the rollers are recessed as shown at 109 to reduce the area of contact between them and the shoulder 10 and marginal flange 12 of the end-closure. It is preferred to employ rollers of as large a diameter as is practicable in order to reduce any tendency to cut into the material of the ridge 11 during the clinching operation. With the rollers mounted on parallel axes, the roller 21 is conveniently made of a sufficiently large diameter to bear against the shoulder 10 at points all round the end-closure, but the diameter of the roller must not be sufficiently

great to prevent removal of the end-closure after clinching.

The rollers 63 and 64 are similarly formed with recesses 109 in their end faces, and when mounted on parallel axes their pressing faces or rims 67 may be slightly tapered in either direction or of cylindrical form and their lower marginal portions are slightly rounded as shown at 68 in Figure 9.

In order that the apparatus may be readily adapted to operate on end-closures of different sizes the rollers 21 and 22 and the rollers 63 and 64 are removably mounted on their shafts 23 and 24 in order to permit them to be readily removed and rollers of different diameters to be substituted.

Instead of inserting the wire in the ridge 11 during the clinching operation performed by the rollers 21 and 22, the wire may be inserted in the ridge 11 before the end-closure is applied to the apparatus shown. The prior insertion of the rip-wire may be carried out for example in the manner described in my Patent 2,213,427. In this case the presser member 30 need not be formed with the passage 39 for the rip-wire. A modified presser member such as may be used instead of the presser 30 is shown in Figure 11 and is indicated by the reference numeral 11. This modified presser member is provided with a toe or curved form as previously described, and the curved surface of the toe may form a continuation of the bottom wall of a groove 18 formed in the body of the presser member. This modified presser member may also be used to co-operate with separate wire-guiding means to facilitate insertion of the wire during the clinching operation, such insertion being effected either manually or by power means.

A further modified presser member 19 is illustrated in Figure 12 and embodies a rotatable roller 81 adapted to fit within the ridge 11 in place of the toe 38. A passage 80 corresponding in location to the groove 18 is formed in the presser member 19 for guiding the rip-wire to the roller 81.

A modified form of clinching apparatus is illustrated in Figure 14 somewhat diagrammatically. The modified apparatus is shown as in operation and in this case the end-closure 41 is driven so as to rotate about its own axis. The end-closure 41 is supported by the holder 28 as before and when moved by the latter towards the clinching means has the upper portion of its central depression urged into frictional engagement with a rotatable plate 84 secured to a spindle 85 which rotates in a bearing 86. The spindle 85 carries a bevel gear 81 which is in mesh with a bevel gear 88 secured to a driving shaft 89 mounted in a bearing 90. When the end-closure 41 is in the position shown it is arranged to be rotated from the shaft 89 either by power means or manually. The gripper rollers are shown at 91 and 92. The roller 91 is secured to a shaft 98 which rotates freely in a stationary bearing 93, while the roller 92 is secured to a shaft 99 which rotates freely in a movable bearing 94. The bearing 94 is carried on a slide 95 which is movable along a guide-way 96 and is urged by a spring 97 in the direction to carry the roller 92 away from the roller 91. Any suitable mechanism such as a cam operated in timed relationship with the shaft 89 may be employed to urge the slide 95 against the spring 97 so as to move the roller 92 bodily

towards the roller 91 and maintain it in clinching position during the clinching operation. The rollers 91 and 92 have their rims tapered oppositely to the rollers 21 and 22 and with a wider angle of taper to suit the angular disposition of their axes. Preferably their portions of greatest diameter are slightly rounded as indicated at 100 to avoid the formation of sharp edges. With the construction of Figure 14 the gripper rollers 91 and 92 may be made of a larger diameter than is possible with the rollers 21 and 22 of Figure 1, since the roller 21 is required to be movable into and out of a space bounded by the ridge 71.

It has already been pointed out that the clinching and pressing of the walls 13 of the ridge 71 should stop slightly short of the ends of the groove; this being desirable to avoid splitting the material of the end-closure at these points. In order further to assist in avoiding such disadvantage the invention provides an improved formation of the ridge at its ends as shown in Figures 15 to 18. The gap in the ridge is indicated at 104. The ridge or groove 47 has an inclined end face 101 as shown most clearly in Figures 16 and 18, the end face 101 being formed with an aperture 102 for the passage of the rip-wire 46. It will be seen that the aperture 102 is raised above the junction of the groove or ridge 47 with those portions of the material of the can end-closure which are displaced laterally of the groove. This is found to assist the clinching of the side walls of the ridge or groove close to the end of the groove without splitting the material of the end-closure and also to facilitate sealing the opening around the rip-wire. The end-closure shown is of the form having a central depression the wall 69 of which is surrounded by a narrow shoulder 70 between which and the marginal flange 72 a groove or ridge 71 is formed.

Figure 19 illustrates a further modification wherein the ridge 71 instead of being discontinuous is formed with a reduced portion at 105 corresponding to the gap 104. The inclined portions 101 and 106 constitute portions corresponding to the end walls of the discontinuous ridge and the aperture 102 for the rip-wire is formed in the portion 101 and is raised above the level of the material on either side of the ridge.

In Figure 18 the wire 46 is shown projecting through the opening 102 and the space between the opening and the wire is shown as being filled up with sealing composition at 103 which may be applied externally or internally and may be extended somewhat beyond the opening 102 on the outside or the inside of the end-closure. The sealing composition may be solder or any other suitable material.

The invention is applicable to the clinching of the material of a portion of a canister around a rip-wire, whether said portion is on the can-body or the end-closure. The invention further extends to the clinching together of the walls of a ridge around a rip-wire on an end-closure whatever the form of the latter. In some cases the end-closure need have no shoulder such as 70 and the ridge may be formed as a continuation of the material forming the central depression. In such a case it may be found desirable to provide aligning means for maintaining the gripper rollers 21 and 22 in their proper relative positions. Such means may comprise a flange provided on one roller above its clinching

surface arranged to engage in a channel-shaped annular groove formed in the other roller above its clinching surface. The rollers 63 and 64 may be provided with similar aligning means.

5 It is to be understood that the invention is not restricted to the precise constructional details shown in the drawings.

I claim:

1. In a method of applying a rip-wire to a container portion having a preformed ridge including spaced walls, the steps including laying the wire into the ridge between said walls, initially compressing the walls progressively about the wire to confine the latter against escape from the ridge, and then progressively compressing the walls further, thereby causing the wire to bite into the inner surfaces of the walls forming lines of weakening therein, and simultaneously converting the ridge into a substantially flat fold upstanding from said portion.

10 15 20 25 30 35 40 45 50 55 60 65 70 75

2. In a method of applying a rip-wire to a container portion having a groove preformed therein, the steps including laying the wire into the groove, initially deforming the groove progressively to convert it into a substantially closed tube and then progressively flattening the tube, thereby causing the wire to bite into the inner surface thereof forming a line of weakening therein, and simultaneously converting the ridge into a substantially flat fold upstanding from said portion.

3. In a method of applying a rip-wire to a container portion having a groove preformed therein, the steps including progressively laying a length of rip-wire into the groove, closing the groove about the wire to confine it therein substantially simultaneously with the laying in of the wire, by progressively deforming the groove and converting it into a substantially closed tube, and then progressively flattening the tube, thereby causing the wire to bite into the inner surface thereof forming a line of weakening therein, and simultaneously converting the ridge into a substantially flat fold upstanding from said portion.

4. Apparatus for applying a rip-wire to a ridge formed in a planar portion of a canister closure and securing it therein comprising a pair of opposed, cooperating preliminary gripping rollers having ridge-shaping surfaces adapted to close said ridge, means mounting said rollers to permit said ridge to be rolled between said surfaces, a second pair of similar gripping rollers having substantially cylindrical shaping surfaces adapted to flatten said ridge, means mounting said second rollers to permit the ridge to be rolled between the shaping surfaces thereof, a closure support, and means mounting said support for movement to place a closure thereon successively in cooperative relation with each of said pairs of rollers, respectively, wire-feeding means associated with said support and movable into feeding relation to a closure on said support for feeding wire into the ridge, and means for advancing said support when in said positions, respectively, to bring a point on said ridge between one pair of rollers, the means for advancing the support when in said position with respect to the first pair of rollers being also effective to advance said wire-feeding means to feeding relation.

5. Apparatus for securing a rip-wire in a ridge formed in a planar portion of a canister closure, said apparatus comprising two opposed gripping rollers having cooperating ridge-shaping surfaces, said rollers being disposed side-by-side and adapted to produce a rolling action on said ridge when it is introduced between said surfaces,

means for supporting said closure with said ridge in position to be engaged progressively by said surfaces, means mounting said supporting means for movement into and out of working position relative to said rollers, wire-feeding means associated with said supporting means adapted to deliver a wire into said ridge while said closure rests on said supporting means and movable into cooperative relation with the closure on the supporting means when the latter is in working po-

10 sition, and common means for actuating said supporting means into said position and said feeding means into said relation.

5 6. The apparatus defined by claim 5 characterized by said feeding means including a presser member having a passage through which the wire passes and a toe adapted to enter said ridge and guide the wire thereinto as it emerges from said passage.

PETER BOGNER.
